UNITED STATES PATENT OFFICE.

THOMAS W. JOHNS, OF BROOKLYN, NEW YORK, ASSIGNOR TO MERGENTHALER LINOTYPE COMPANY, A CORPORATION OF NEW YORK.

SLUG-CASTING MACHINE.

1,277,598.

Specification of Letters Patent.

Patented Sept. 3, 1918.

Application filed August 16, 1917. Serial No. 186,486.

To all whom it may concern:

Be it known that I, THOMAS W. JOHNS, a citizen of the United States, residing at Brooklyn, in the county of Kings and State 5 of New York, have invented certain new and useful Improvements in Slug-Casting Machines, of which the following is a specification, reference being had therein to the accompanying drawing.

- 10 My invention relates to typographical machines such as linotype machines of the general organization represented in Letters Patent of the United States No. 436,532, to O. Mergenthaler, wherein molten metal is 15 forced from a casting pump into a slotted mold against a composed line of matrices to produce a printing slug or linotype, which is subsequently removed from the mold by an ejector advancing from the rear and 20 driving the slug before it into a receiving galley at the front of the machine.

In these machines, it is frequently necessary to vary the length of the mold slot in order to produce slugs of different lengths, 25 and this involves a corresponding change in the width of the ejector, which of course must be narrow enough to enter the mold. In practice, it occasionally happens that the attendant, through ignorance or carelessness, 30 fails to perform both of these two necessary operations, but instead reduces the length of the mold slot without correspondingly reducing the width of the ejector, which therefore is almost certain to damage or injure 35 the parts.

It is the aim of my present invention to obviate these objections and to protect the parts against injury, even in the event of the failure of the attendant to make the required 40 adjustments. To this end, specifically, I employ a locking device to hold the mold disk normally against rotation and thus to prevent the adjustment of the mold slot, and provide connections whereby the unlocking 45 of the mold disk simultaneously effects the disconnection of the ejector from its operating devices and the locking of the casting pump, means also being employed to hold the parts in this condition until the ejector 50 is changed and drawn forward by hand into the mold slot after the rotary adjustment of the disk. If the ejector fails to enter the slot because of its excessive width or for any other reason, the parts remain unaffected, 55 but if it enters, then they are released and

restored to their normal condition upon the subsequent withdrawal of the ejector. In other words, although the machine itself is allowed to complete its usual cycle of operation, both the ejector and the pump are 60 rendered inactive whenever or before the mold apparatus is adjusted, and these parts cannot be restored to action until the ejector is adjusted and caused to enter the new mold slot, thus making it necessary that the blade 65 be of proper width, and avoiding any injury to the parts if the ejector is larger than the mold. These and other features will more fully appear in the detailed description to follow.

In the accompanying drawing, I have shown my invention merely in preferred form and by way of example and as applied to a machine of the class stated, but obviously it is susceptible of various alterations 70 and modifications which will still be comprised within its spirit. Generally speaking, I desire it to be understood that I do not limit myself to any specific form or embodiment, except in so far as such limitations are specified in the claims.

Referring to the drawings:

Figure 1 is a perspective view of my improvements as applied to a linotype machine; and

Fig. 2 is a side elevation showing the parts in different positions.

The slug casting molds A, having slots of different lengths, are carried by the disk B, which is rotatably mounted upon the supporting slide B¹ so as to present the active mold first in a horizontal position for casting and subsequently to locate it in the vertical position shown in Fig. 1, where it stands in front of the ejector C, attached to 90 the slide C¹, which is arranged to be reciprocated forwardly and backwardly within the mold slide B¹, first, to drive the ejector through the mold to remove the slug 95 therefrom and, then, subsequently to withdraw the ejector from the mold, when the parts come to rest. The movement of the ejector slide C¹ is effected by means of the pivoted upright lever C² connected thereto by the link C³ and which is rocked to and 100 fro by rotary cams on the main shaft of the machine. The periodic rotations of the mold wheel B are controlled by the driving pinion B² operated through the usual connections from the main shaft.

The pinion B^2 is arranged to be pulled forwardly by hand to break its connection with its driving shaft, and when thus disconnected, it is turned independently to set 5 the disk B with one or another of the molds thereon in active position, after which the pinion is re-connected to its shaft, all as shown and described in the Randall Patent No. 758,103. It is in this way that the mold 10 apparatus is adjusted to effect a change of mold slot, although such adjustment might be effected in any other manner, *e. g.*, in the case of a single mold, by the employment of interchangeable filling pieces or liners.

15 In the present instance, the ejector C is of the form shown and described in the Rogers Patent No. 967,976, comprising a series of independent blades or sections arranged edge to edge and any selected number 20 of which may be connected to the slide C^1 at will, such connection being controlled by the vertically adjustable member C^4 which is operated in the usual way from the hand lever C^5 . The ejector is thus adapted to be 25 changed in width to correspond to any length of mold slot employed. There are other ways in which this change or adjustment of the ejector may be effected if desired, as, for instance, by detaching the 30 blade from the slide and substituting another of the required width, or by employing a set of integral blades of the different required widths which can be adjusted laterally to connect any selected one thereof 35 with the ejector slide.

The parts so far described are all of well known construction, and except as herein-after pointed out constitute in themselves no part of my present invention. As before 40 stated, it is the aim of my invention to insure the corresponding adjustments of the mold apparatus and the ejector, and to avoid injury to the parts in the event that the attendant should fail to reduce the size 45 of the ejector in changing from a larger to a smaller mold; and the manner in which these results are accomplished will now be described.

As shown in any of the figures, the ejector 50 link C^3 is provided at its forward end, as usual, with a circular head portion c fitting into a corresponding socket c^4 in the ejector slide C^1 , the latter also being formed with a flared notch c^2 to allow the link to be 55 rocked upwardly and downwardly about its forward end as a pivot. At its rear end, the link is formed with an open slot c^3 fitting over the cross pin c^4 carried by the upright operating lever C^2 . As a result, by raising 60 and lowering the link C^3 it may be disengaged from or reengaged with the operating lever C^2 at will, thus breaking or making the operative connection of the ejector with its power-operated devices. The raising and 65 lowering of the link is effected by a vertical

movable rod D supported at its lower end upon a fixed pin D^1 , which engages in an elongated slot D^2 formed in the rod. At its upper end, the rod passes between a pair of laterally projecting pins D^3 on the ejector link C^3 , and is provided with a pin or roller D^4 engaging the lower edge of the link. To operate the rod D , there is employed a long foot lever D^5 pivoted centrally, as at D^6 , to a fixed part of the framework, and having its rear end passing loosely between a pair of pins D^7 on the rod, and presenting at its forward end a treadle portion D^8 exposed at the front of the machine. Under this arrangement, the attendant by pressing down upon the foot lever may, through the above connections, effect the instantaneous disconnection of the ejector (Fig. 2).

To insure this disconnection of the ejector before effecting a change of mold slot, there is provided a locking pawl H which holds the mold disk B against rotation until the foot lever D^5 is operated. This locking pawl is carried by an arm H^1 projecting laterally from the foot lever, and a spring H^2 connected to the lever tends constantly to hold the pawl in engagement with the teeth of the mold disk. It is apparent, therefore, that no adjustment of the mold disk to effect a change of mold slot can take place until the foot lever is operated, which then not only releases the mold disk but conjointly therewith effects the disconnection of the ejector from its power-operated devices. (Fig. 2).

When the foot lever D^5 is thus operated, means are provided to lock it in its operated position so as to maintain the disconnection of the ejector until it is properly adjusted in width to correspond to the new length of mold slot selected by the rotary adjustment of the mold disk. In the present instance, this feature is realized by attaching to the lower end of the vertical rod D a pivoted gravitating or spring-actuated pawl E , which when the rod is raised swings forwardly above a fixed lug or shelf E^1 , thus holding the rod in its raised position and consequently maintaining the ejector link C^3 disconnected from the operating lever C^2 (Fig. 2). Also attached to the rod D is an actuating link F having an operating hand lever F^1 exposed at the front of the machine within reach of the operator. This actuating link F is pulled forwardly when the rod D is in its raised position, so as to rock said rod forwardly about the pin D^1 as a pivot, and through the medium of the ejector link C^3 and the slide C^1 to draw the ejector C forwardly from its normal position of rest. If the ejector has been changed or is of proper width, it will enter the mold as the rod D is rocked forwardly, and this rocking of the rod will trip the pawl E by swinging it rearwardly beyond the lug E^1 (see dotted lines of Fig. 2), thus allowing the 130

rod to fall and the ejector link C^3 to drop and become engaged with the operating lever C^2 upon the subsequent withdrawal of the ejector from the mold (Fig. 1). If, on the other hand, the ejector has not been changed or is too large to enter the mold, the ejector cannot be drawn forward and hence no rocking movement of the rod D takes place, so that the pawl E remains engaged with the lug E^1 and maintains the ejector link disengaged from the operating lever C^2 . The effect of this arrangement is that when the ejector is disconnected from its power-operated devices, the parts are locked in this condition until the ejector is drawn forwardly, which can only be done when it is of the proper width. In this way, it becomes necessary for the operator to test out the size of the blade before the parts can be restored to action, although this restoration is effected automatically when the ejector is of proper width and is drawn forwardly into the mold. If desired, the ejector link C^3 may be provided at its rear end with a hook c^5 to engage the pin c^4 of the operating lever C^2 when the link is moved forwardly by the rocking of the rod D , and thus to limit the forward movement of the disconnected ejector.

It has been mentioned above that the disconnection of the ejector is effected without interfering with the operation of the machine itself, which is allowed to complete its usual cycle of operation while the ejector remains inactive. Since the machine is thus allowed to operate, it is evident that the casting pump would also be actuated to force the molten metal into the mold in the usual manner, and in such event, the ejector being out of action, the slug would remain in the mold and cause injury to the parts. Means are therefore provided to lock the casting pump against action simultaneously with the unlocking of the mold disk and the disconnection of the ejector, so that if the machine is thereafter operated no damage can result. Only the pump plunger K and its operating arm K^1 are herein shown, as the construction and operation of the pump are well known in the art. There is associated with the actuating lever K^1 , as usual, a pivoted locking dog K^2 , one end of which is adapted to engage beneath a lug K^3 projecting laterally from the lever, and the other end of which is engaged by the conical end of a vertical rod K^4 passing through a bracket plate K^5 attached to the justification lever J . The spring K^6 attached to the locking dog K^2 tends constantly to hold the latter free and clear of the pump actuating lever K^1 , but this tendency of the spring is overcome by the rod K^4 when the latter is raised by an excessive upward movement of the justification lever, which takes place when the composed line is not filled out

properly, all as well understood in the art. In the present instance, the dog K^2 and rod K^4 are utilized to lock the pump against action when the ejector is disconnected from its power-operated devices. For this purpose, the rod K^4 is arranged in engagement at its lower end with a lug or shelf K^7 projecting laterally from the foot lever D^5 beyond its pivotal point. As a result, when the foot lever is depressed to unlock the mold disk and to disconnect the ejector, it simultaneously raises the rod K^4 , which throws the dog K^2 beneath the pump actuating lever K^1 and locks it against movement (Fig. 2), the parts being held in this condition until the ejector is drawn forward in the manner before described, due to the connection of the foot lever with the rod D carrying the pawl E . It follows, therefore, that the mold slot cannot be changed until the casting pump is first locked against action, and that the pump cannot be unlocked until the ejector is properly changed to accord with the new mold slot or drawn forwardly thereinto, which latter operation effects the unlocking of the pump automatically.

As during the normal operation of the machine it is necessary that the mold disk B be free for rotation, means are provided to effect the disengagement of the locking pawl H therefrom during its automatic periods of rotation. In the present instance, this is accomplished by extending downwardly from the arm H^1 a hook-shaped member H^3 to engage beneath the usual justification lever J , it being pointed out that during the operation of the machine the justification lever is depressed at times preceding the rotation of the disk, as is well understood. The automatic disengagement of the locking pawl H will, because of its rigid connection with the foot lever D^5 , rock the latter idly about its pivot, which is permitted by a sufficient amount of play between the connected parts.

In order to clean the back of the mold and for other reasons, it is sometimes desirable to disconnect the mold slide B^1 from its operating devices and to draw it forwardly by hand. In performing this manual operation, it is customary to disconnect the ejector from its operating devices also, because of the fact that the ejector slide is carried by the mold slide. This second operation is rendered unnecessary in the present arrangement by extending downwardly from the mold slide B^1 an arm L formed with a cam piece L^1 which is arranged to engage a coöoperating cam piece L^2 located on the foot lever D^5 in the rear of its pivot. Consequently, when the mold slide is drawn forwardly, the engagement of the two cam pieces rocks the foot lever upwardly at its rear end, and through the medium of the

- rod D raises the ejector link C³ out of engagement with the operating lever C², in precisely the same manner as if the foot lever were depressed by the attendant.
- 5 The operation of the several parts will have been understood from the foregoing description. It suffices to say here that in making a change of mold slot, it is necessary for the operator to depress the foot lever D⁵ to unlock the mold disk, and this depression of the foot lever through the connections described effects the locking of the pump and the disconnection of the ejector from its power-operated devices, the parts being maintained or locked in this condition by the pawl E which remains active until the ejector is drawn forwardly and caused to enter the mold, when the parts are restored upon the withdrawal of the ejector from the mold. If the ejector is not so manipulated either because of its excessive width, or for any other reason, the pump remains locked and the ejector disconnected, even though the machine is allowed to operate.
- 10 25 As previously stated, I have shown my invention merely in preferred form and by way of example and as applied to a specific style of machine. However, many modifications and alterations therein, and in its mode of application, will readily suggest themselves to those skilled in the art without departure from its scope. It will also be observed that while the several features of my improvements are all involved in accomplishing the objects aimed at, many of them are such as might be used to advantage either individually or in other combinations. Thus, the feature of effecting the locking of the casting pump by the unlocking of the mold disk preparatory to its adjustment, and that of preventing the unlocking of the pump until the ejector is drawn forward into the mold, might be useful alone or apart from their association with the features involving the disconnection of the ejector by the unlocking of the disk and the automatic re-connection of the ejector when it is caused to enter the mold, or vice versa. Again, the feature of automatically disconnecting the ejector from its power-operated devices when the mold slide is drawn forwardly by hand could be used alone or in other combinations as well, and the same is true of the locking device for the mold disk, etc. It is therefore to be understood that my invention is not to be limited to any features of construction or combinations of said features, except in so far as such limitations are specified in the claims.
- 15 20 25 30 35 40 45 50 55 60 Having thus described my invention, its construction and mode of operation, what I claim and desire to secure by Letters Patent of the United States, is as follows:
- 65 1. In a slug casting machine, the combination of a mold apparatus adjustable to provide mold slots of different lengths, an ejector to remove the cast slugs and capable of being rendered inactive at will, and means to prevent the adjustment of the mold apparatus until the ejector is rendered inactive.
2. In a slug casting machine, the combination of a mold apparatus adjustable to provide mold slots of different lengths, an ejector to remove the cast slugs, power-operated devices connected to the ejector and capable of disconnection therefrom at will, and means to prevent the adjustment of the mold apparatus until the ejector is disconnected from its power-operated devices.
3. In a slug casting machine, the combination of a mold apparatus adjustable to provide mold slots of different lengths, an ejector to remove the cast slugs, locking means to prevent the adjustment of the mold apparatus, and connections whereby the release of the mold apparatus renders the ejector inactive.
4. In a slug casting machine, the combination of a mold apparatus adjustable to provide mold slots of different lengths, an ejector to remove the cast slugs, power-operated devices connected to the ejector, locking means to prevent the adjustment of the mold apparatus, and connections whereby the release of the mold apparatus effects the disconnection of the ejector from its power-operated devices.
5. In a slug casting machine, the combination of a mold apparatus adjustable to provide mold slots of different lengths, an ejector to remove the cast slugs, power-operated devices connected to the ejector, locking means to prevent the adjustment of the mold apparatus, means for disconnecting the ejector from its power-operated devices, and a common actuating device or foot lever connected to both of said means and adapted when operated to effect the release of the mold apparatus and the disconnection of the ejector.
6. In a slug casting machine, the combination of a mold apparatus adjustable to provide mold slots of different lengths, a casting apparatus capable of being rendered inactive at will, and means to prevent the adjustment of the mold apparatus until the casting apparatus is rendered inactive.
7. In a slug casting machine, the combination of a mold apparatus adjustable to provide mold slots of different lengths, a casting pump having locking means therefor, locking means to prevent the adjustment of the mold apparatus, and connections between the two said locking means whereby the unlocking of the mold apparatus effects the locking of the pump.
8. In a slug casting machine, the combination of a mold apparatus adjustable to

provide mold slots of different lengths, a casting apparatus, an ejector, means whereby the casting apparatus and the ejector may be rendered inactive at will, and means 5 to prevent the adjustment of the mold apparatus until both the casting apparatus and the ejector are rendered inactive.

9. In a slug casting machine, the combination of a mold apparatus adjustable to provide mold slots of different lengths, a casting apparatus, an ejector, locking means to prevent the adjustment of the mold apparatus, and connections whereby the release of the mold apparatus renders both the 15 casting apparatus and the ejector inactive.

10. In a slug casting machine, the combination with a mold apparatus adjustable to provide mold slots of different lengths, a casting pump, an ejector, and power-operated devices connected to the ejector, of locking means to prevent the adjustment of the mold apparatus, locking means to prevent the action of the pump, means for disconnecting the ejector from its power-operated devices, and a common actuating 20 device or foot lever connected to all of said means and adapted when operated to effect the unlocking of the mold apparatus and conjointly therewith the locking of the 25 pump and the disconnection of the ejector.

30 11. In a slug casting machine, the combination of a mold apparatus adjustable to provide mold slots of different lengths, an ejector changeable to correspond and capable of being rendered inactive at will, means to prevent the adjustment of the mold apparatus until the ejector is rendered inactive, and means to prevent the action of the ejector until its proper change has been effected.

40 12. In a slug casting machine, the combination of a mold apparatus adjustable to provide mold slots of different lengths, an ejector changeable to correspond, power-operated devices connected to the ejector 45 and capable of disconnection therefrom at will, means to prevent the adjustment of the mold apparatus until the ejector is disconnected from its power-operated devices, and means to prevent the re-connection of the 50 ejector until its proper change has been effected.

13. In a slug casting machine, the combination of a mold apparatus adjustable to provide mold slots of different lengths, an 55 ejector changeable to correspond, locking means to prevent the adjustment of the mold apparatus, connections whereby the release of the mold apparatus renders the ejector inactive, and means to prevent the action of the 60 ejector until its proper change has been effected.

14. In a slug casting machine, the combination of a mold apparatus adjustable to provide mold slots of different lengths, an 65 ejector changeable to correspond, casting

apparatus capable of being rendered inactive at will, means to prevent the adjustment of the mold apparatus until the casting apparatus is rendered inactive, and means to prevent the action of the casting apparatus 70 until the proper change of the ejector has been effected.

15. In a slug casting machine, the combination of a mold apparatus adjustable to provide mold slots of different lengths, an 75 ejector changeable to correspond, a casting pump having locking means therefor, locking means to prevent the adjustment of the mold apparatus, connections between the two locking means whereby the unlocking of the 80 mold apparatus effects the locking of the pump, and means to prevent the unlocking of the pump until the proper change of the ejector has been effected.

16. In a slug casting machine, the combination of a mold apparatus adjustable to provide mold slots of different lengths, an ejector changeable to correspond, casting apparatus, means whereby the casting apparatus and the ejector may be rendered inactive at will, means to prevent the adjustment of the mold apparatus until both the casting apparatus and the ejector are rendered inactive, and means to prevent the action of these parts until the proper change of the 95 ejector has been effected.

17. In a slug casting machine, the combination of a slotted mold, an ejector to remove the slugs therefrom, means for rendering the ejector inactive at will, and 100 means to prevent the subsequent action of the ejector until it is first caused to enter the mold slot.

18. In a slug casting machine, the combination of a slotted mold, an ejector to remove the slugs therefrom, power-operated devices connected to the ejector, means whereby the ejector may be disconnected from its power-operated devices at will, and means to prevent the subsequent re-connection of the ejector until it is first caused to enter the mold slot. 105

19. In a slug casting machine, the combination of a slotted mold, an ejector to remove the slugs therefrom, power-operated 115 devices connected to the ejector, means whereby the ejector may be disconnected from its power-operated devices at will, and means to maintain the ejector so disconnected, said means being arranged to be released by the movement of the disconnected ejector into the mold slot.

20. In a slug casting machine, the combination of a slotted mold, an ejector to remove the slugs therefrom, casting apparatus, means for rendering the casting apparatus inactive, and means to prevent the subsequent action of said casting apparatus until the ejector is first caused to enter the mold slot. 125

21. In a slug casting machine, the combination with a slotted mold, a casting pump, an ejector, and power-operated devices connected to the ejector, of means for locking the pump against action and for disconnecting the ejector from its power-operated devices, and means to maintain the parts in this condition, said means being arranged to be released by the movement of the disconnected ejector into the mold slot.
22. In a slug casting machine, the combination of a mold, an ejector to remove the slugs therefrom, power mechanism for the several operative parts including the ejector, and means for disconnecting the ejector therefrom while allowing the machine to complete its cycle of operation.
23. In a slug casting machine, the combination of an ejector slide, a power-operated lever, a link connecting the slide and lever and arranged to be shifted out of engagement with the latter, a movable rod connected to the link to effect such shifting thereof, an automatic pawl carried by said rod to hold it in its moved position, and an actuating member connected to the lifting rod for drawing the disconnected ejector forwardly, for the purpose described.
24. In a slug casting machine, the combination of an ejector slide, a power-operated lever, a link connecting the slide and lever and arranged to be shifted out of engagement with the latter, a lifting rod connected to the link to effect such shifting thereof, a pivoted foot lever for operating the rod and exposed at the front of the machine, an automatic pawl carried by the lifting rod to hold it in its raised position, and a hand-actuated member also connected with the lifting rod for drawing the disconnected ejector forwardly for the purpose described.
25. A structure as specified in either of claims 1 to 16, characterized by the fact that the adjustable mold apparatus therein referred to comprises a plurality of different sized molds carried by a rotary disk or wheel which may be set in different positions to bring any selected one of the molds into action.
26. In a slug casting machine, the combination of a rotary mold disk or carrier adapted to be rotated periodically during the operation of the machine, a locking device normally engaged with the mold disk, and automatic means for momentarily disengaging the locking device from the mold disk during the periodic rotations of the latter.
27. In a slug casting machine, the combination of a rotary mold disk or carrier adjustable when the machine is at rest to bring different molds into use, rotating mechanism for the mold, a locking device independent of the rotating mechanism to prevent the adjustment of the mold disk, and manually operated means to disengage said locking device.
28. In a slug casting machine, the combination of a mold slide adapted to be drawn forwardly by hand when disconnected from its actuating parts, an ejector slide carried by the mold slide, power-operated devices connected to the ejector slide, and means actuated by the forward manual movement of the mold slide for disconnecting the ejector slide from its power-operated devices.
29. In a slug casting machine, the combination of a mold slide adapted to be drawn forwardly by hand when disconnected from its actuating parts, an ejector slide carried by the mold slide, a power-operated lever, a link connecting the ejector slide and lever and arranged to be shifted out of engagement with the latter, and connections whereby the forward movement of the mold slide effects such shifting of the connecting link.
30. In a slug casting machine, the combination of a mold slide adapted to be drawn forwardly by hand when disconnected from its actuating parts, an ejector slide carried by the mold slide, a power-operated lever, a link connecting the ejector slide and lever and arranged to be shifted out of engagement with the latter, a vertically movable rod connected to the ejector link to effect its disengagement from the lever, a pivoted foot lever for operating the movable rod and provided back of its pivot with a cam piece, and an arm depending from the mold slide and provided with a cam piece to coöperate with that on the foot lever when the mold is drawn forward by hand and effect the disconnection of the ejector slide from its power-operated lever.

In testimony whereof, I have affixed my signature.

THOMAS W. JOHNS.
